MOLD SHOE FOR MAKING CONCRETE BLOCKS

Loring Pickering, 5005 Townsend Way,
Bladensburg, Md. 20710

Filed Sept. 23, 1968, Ser. No. 13,659

Term of patent 14 years

Int. Cl. D15—99

U.S. Cl. D55—1

FIG. 1

FIGURE 1 is a perspective view of a mold shoe for making concrete blocks showing my design.

FIGURE 2 is a side elevational view thereof.

FIGURE 3 is a top plan view.

FIGURE 4 is an elevational view of the opposite side of the shoe.

FIGURE 5 is a bottom plan view thereof.

FIGURE 6 is an end elevation thereof.

I claim:

The ornamental design for a mold shoe for making concrete blocks, as shown.
